COOKING APPARATUS

Walter Koziol, Russell, Ill., assignor to Charmglow Manufacturing Co., Antioch, Ill., a corporation of Illinois

Filed Nov. 19, 1968, Ser. No. 14,539

Term of patent 14 years

Int. Cl. D7—04

U.S. Cl. D81—10

FIG.1

FIG.4

FIG. 5

FIG. 6

FIG. 7

FIG. 1 is a perspective view of a cooking apparatus showing my design;

FIG. 2 is a side view in elevation of the cooking apparatus shown in FIG. 1;

FIG. 3 is a front view in elevation of the apparatus shown in FIG. 1;

FIG. 4 is a back view in elevation of the FIG. 1 apparatus;

FIG. 5 is a perspective view of another embodiment of a cooking apparatus showing my design;

FIG. 6 is a back view in elevation of the cooking apparatus shown in FIG. 5; and

FIG. 7 is an end view taken along line 7-7 of FIG. 6.

The dominant features of my design reside in the portions shown in full lines. The broken line showing of a support pole in all of the figures and the handle in FIGS. 1, 2, 3, 5 and 7 are for illustrative purposes only.

What is claimed is:

The ornamental design of a cooking apparatus, substantially as shown and described.
